UNITED STATES PATENT OFFICE.

ABSALOM BACKUS, JR., OF DETROIT, MICHIGAN.

FURNACE.

SPECIFICATION forming part of Letters Patent No. 365,772, dated July 5, 1887.

Application filed March 23, 1887. Serial No. 232,657. (No model.)

To all whom it may concern:

Be it known that I, ABSALOM BACKUS, Jr., a citizen of the United States, residing at Detroit, in the county of Wayne and State of Michigan, have invented certain new and useful Improvements in Furnaces; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 This invention relates to the construction of a furnace for generating steam and like purposes, the object of which is to so construct the furnace that the products of combustion shall be properly and sufficiently consumed, thereby saving a large portion of fuel which is lost as furnaces are now constructed; also avoiding the smoke nuisance, which is the result of improperly-constructed furnaces, allowing the volatile particles of combustion to escape in the form of gases and carbonic acid, smoke, or soot, all of which results from improper construction, manner of feeding the fuel, and a lack of proper draft or introduction of air to properly aid combustion.

20 These objections are effectually overcome by my present invention, which consists in the organization or construction of parts, as hereinafter fully set forth, and pointed out particularly in the claims.

25 In the drawings, forming a part of the specification, Figure 1 is a front perspective of a furnace containing my invention, having the iron front below the boiler broken away. Fig. 2 is a vertical central section taken on dotted line xx of Fig. 1 and looking toward the left, the iron front not being broken away, as in Fig. 1.

30 B in the drawings represents the boiler; B', the brick-work; D, the bridge-wall; t' , the top of said wall, and f the sloping front to said wall.

35 G is a dumping-grate, which I locate along the incline of the bridge-wall at the bottom of the incline. (See Fig. 2.) The rear edge of the dumping-grate is provided with pivot-bearings a' , with a depending arm, t , which has a pivotal connection with the ver-

tical bar c . The bar c has a pivotal connection with the anchor-arm a , secured to the bridge-wall.

40 r is a rod, which I pivotally attach to the joining ends of the arm t of the dumping-grate and the bar c , as shown in Fig. 2.

O' is a transverse bar having its ends anchored in the side walls, S S, of the furnace. O This bar supports the rear ends of the grate-bars Z. The upper faces of the grate-bars are located on a horizontal plane with the upper face of the dumping-grate G, both standing on an incline, as shown in Fig. 2, the front ends of the grate-bars being lower than the rear ends.

45 O is a cross-bar supporting the front of the grate-bars. Its ends are anchored in the side walls, S S, of the furnace, and it is supported at the center by the central or dividing wall, C, which extends from the bottom of the ash-pit upward, meeting and supporting the joining sides of the arched walls A A, as shown in Fig. 2. The opposite sides of the arched walls are anchored to the side walls of the furnace.

50 F represents the common iron front of a furnace, having the usual feed-door, F', and doors N to ash-pit. The supporting-bar O, I locate back of the iron front about ten inches. The grate-bars Z project forward of said bar O and meet the inner face of the iron frame F, as shown in Fig. 2. The front end, E, of the central wall stands on a vertical line with the front face of the supporting-bar O. (See Fig. 2.)

55 P represents a pillar or support, which I form of a single layer of fire-brick, and locate it in front of the front end, E, of the central wall, C. Its upper end supports the arches A A at the front, as shown in Fig. 1, and stands flush with the back inner face of the front, as shown in Fig. 2. This construction forms a vertical chamber, H, leading from the bottom of the ash-pit to the point of juncture of the arches. This is an air-induct for feeding the flames under each arch or to the retorts R R. The inner faces of the side walls, S S, terminate at the front on a line with the central wall, C, and I locate in front of such terminations the single brick pillars or supports P' P', the front faces of which also meet the back face of the iron front F. This construction forms air inducts or flues H' H' in the sides of the furnace,

leading from the bottom of the ash-pit *m* to the under face of the arches *A A*, and at the front ends. These I also employ for admitting air into the front ends of the retorts *R R*.

5 In operating my furnace the fuel is placed on the grates of each retort *R* through the common feed-doors *F'*, the coal or fuel when placed on the grates should lie back of the bar *O*, supporting the grates; or, in other words, 10 that portion of the grates projecting forward of said bar should be left clear, so as to allow the air to freely pass up at the front and into the retorts at the front ends. When the furnace has been charged with fuel, the feed-doors 15 are to be closed. The furnace or retorts *R R* are supplied freely with air through the open spaces at the front ends of the grate-bars and through the air-inducts *H H' H'*. The air passes upward from the ash-pit, and the 20 draft may be regulated by the doors *N* at the ash-pit. To replenish the fuel, the operator first shoves the burning products back on the grates and charges the retorts, as before. The 25 length of the arches *A A* and the central wall, *C*, is about two-thirds the length of the grate-bars. The intense or incandescent heat is at the 30 rear ends of the arches under the boiler; and as the upper walls of the arches are on a horizontal line, locating the rear ends of the grate-bars higher than the front ends narrows the 35 discharge at the rear ends of the retorts *R R* and enables me to locate the dumping-grate nearer the boiler, thus making the rear end of the furnace more shallow, and bringing the flames 40 nearer the shell of the boiler, where they belong; and as I give the front upper face of the bridge-wall the incline of the flames are gradually and without interruption brought against the shell of the boiler, thereby rapidly generating steam.

Having thus fully set forth my invention, what I claim as new, and desire to secure by Letters Patent, is—

1. In a furnace, the combination of the side

walls, the central wall, the arched walls joining 45 said central and side walls, a set of grate-bars located under each arched wall, the furnace-front having feed-openings above the grate-bars, and the central and side air-flues leading from below the grate-bars into the front end 50 of the retorts, substantially as and for the purposes specified.

2. In a furnace, and in combination, the side walls, the boiler, the arched walls located horizontally below the boiler, the central wall supporting 55 said arched walls, its front end terminating some distance back from the front of the furnace, the inner face of the side walls having a like termination, forming the air-flues leading from the ash-pit to the arched 60 walls *A*, the set of grate-bars located below each arched wall upon transverse supports, so as to bring the rear ends of the grate-bars on a higher plane than the forward ends, the furnace-front having feed-doors opening into the 65 retorts, and doors opening into the ash-pit, as and for the purposes specified.

3. In a furnace, the combination of the boiler, the side walls having the air-flues *H' H'*, the arched walls located horizontally below the 70 boiler, the central wall supporting said arched walls, its front end terminating some distance back of the furnace-front, forming the central air-flue, the set of grate-bars located below each arched wall upon the transverse bars, as 75 specified, the bridge-wall having the rearwardly-inclined front, the dumping-grate and mechanism for operating said dumping-grate, the furnace-front, and supports *P P' P'*, meeting the inner face of said front, as and for the 80 purposes specified.

In testimony whereof I affix my signature in presence of two witnesses.

ABSALOM BACKUS, JR.
